UNITED STATES PATENT OFFICE.

MANUEL HUMBERTO PÉREZ, OF SAN PEDRO SULA, HONDURAS.

PHONOGRAPH RECORD REPEATER.

Application filed October 8, 1923. Serial No. 667,341.

This invention relates to phonograph record repeaters, and one object of the invention is to provide a repeater which may be used on various makes of talking machines, and in connection with disk records of various sizes, and which will operate automatically to return the needle to starting position for the playing of a record as many times as desired.

10 A further object of the invention is to provide a record repeater which is readily and conveniently adjustable for use in connection with a record of any given size between minimum and maximum.

15 A still further object of the invention is to provide a record repeater which is simple of construction, efficient in operation, and adapted to be readily applied and adjusted for use, and which may generally simulate 20 in appearance a serpent or scroll-shaped body of suitable design, thus serving as a novelty as well as an article of utility of the character described.

The invention consists of the features of 25 construction, combination and arrangement of parts, hereinafter fully described and claimed, reference being had to the accompanying drawing, in which:

30 Figure 1 is a plan view of a phonograph record repeater embodying my invention.

Figures 2, 3, 4 and 5 are, respectively, sections on the lines 2—2, 3—3, 4—4 and 5—5 of Figure 1.

In carrying my invention into practice, I 35 provide a phonograph record repeater which, in the form disclosed, comprises two unitary plate-like members 1 and 2, the member 1 constituting the main part of the device and the member 2 an adjustable needle guide, as 40 hereinafter described. These members 1 and 2 may be made of sheet metal or other sheet material of requisite thickness, strength and durability, stamped or otherwise fashioned into shape and which may be made plain or 45 unfinished, or finished or ornamented in any desired manner according to the taste or fancy of the manufacturer or demand of the purchasing public.

The member 1 consists of oppositely ex- 50 tending arms or portions 3 and 4, united at their adjacent ends by a U-shaped or arcuately curved offset portion 5, and thence ex-

tending in reverse directions on desired lines of curvature. The arm 3 terminates at its free end in an inwardly bent or curved head 55 6, around the inner side of which is provided an upstanding guide rib 7. Provided for cooperation with this rib is a stop rod 8 having a beveled or tapered inner end 9 and provided at its opposite end with a knob or finger piece 10. This rod is adjustable to greater or less degrees beyond the outer end of the rail 7 in a guide sleeve 11 carried by the head 6 and is provided with a longitudinal groove 12 receiving a set screw 13 65 on the sleeve, whereby said rod is held from rotation and whereby it may be fixed in adjusted position, as will be readily understood.

The arm 4 terminates at its free end in a disk or head 14, arranged opposite the head 70 6, which head 14 is provided with an opening 15 for the passage of the rotating turntable spindle of the phonograph machine. Provided on said head 14, in alignment with said opening 15, is a clutch head or ferrule 75 16 slotted to provide a series of spring gripping fingers 17. These fingers are designed to grip the spindle with sufficient force to couple the repeater for rotary movement with the turntable and record when the repeater is not positively held from movement, but have a light enough grip to slip upon the spindle to prevent the repeater from rotating the turntable and record while the composition is being played and during 80 which time the reproducer needle engages the ribs 7 or rod 8 and holds the repeater from rotation.

Formed integrally with the arm 4 is a substantially V-shaped or triangular web 18, the widened outer edge portion of which intersects the arm 4 and the narrower or vertex end portion of which extends inwardly in proximity to the offset 5. This part 18 is provided with guide ribs or rails 19 forming 90 the initial portion of a return groove or channeled guideway for the needle. These ribs or rails 19 are arranged in close relation and approximately parallel at their inner ends along the narrow portion of the part 18, 100 and flare outwardly and rearwardly to provide with the web portion 18 of the plate a flaring entranceway 20 to said initial portion of the guide groove or guideway. To

facilitate the entrance of the needle into said portion 20, the marginal edge of the plate 18 is formed with a beveled or inclined surface 21, up which the needle may easily ride. A brace 22 of suitable form lying on the opposite side of part 18 from the forward portion of the arm 4 may connect the head 14 and outer end of arm 4 at a point opposite the inner end of arm 4 with the inner end 19 of part 18, thus mutually bracing and reinforcing said parts and forming an additional support to rest upon the surface of the record desirably increasing the area of the device as a whole to prevent the device from tilting and adapt the same to rest stably upon the record when in use.

The member 2 is arranged to lie between the arms 3 and 4 and is provided at one end with an expanded disk-shaped portion or head 23 arranged to underlie the upwardly offset, substantially hemispherical portion 24 of a bracket plate 25 riveted or otherwise suitably secured to the offset 5, said disk or head 23 being pivotally connected with the part 24 by a pin or rivet 26. The arm 2 is suitably grooved and is provided with spaced guide rails 27 to form a channeled guideway constituting the delivery portion of the return groove or guideway for the needle, said delivery portion and the initial portion, hereinbefore referred to, being designed to provide a spiral channeled guideway of suitable spiral contour, the contour of which may be varied by adjusting the member 2 on its pivotal connection 26 and in an arc radially with respect to the head 24 and turntable spindle and center of the record engaged therewith. The rails 27 are uniformly spaced to provide a comparatively narrow guideway except at their inner ends where they are slightly spread or flared to provide an entrance portion 28 designed to register with the inner end of the initial portion of the guideway in any of the positions to which the member 2 may be adjusted, for the certain guiding of the needle from one portion to the other of said guideway. The free end of the member 2 terminates in working proximity to the head 6 and is provided with forked portions 29 defining a space or recess 30 designed to align with the first groove of the record so as to form a starting recess receiving the needle and whereby the needle is delivered from the return groove of the repeater into the starting groove of the record. As shown, the upper or head portion 24 of the bracket plate 25 overhangs the segmental recess formed by the offset portion 5 connecting the arms 3 and 4, and said head portion 24 is connected with the bracket plate 25 proper by a segmental vertical wall 24^a. The bracket head portion 24 thus overlies that portion of the disk 23 on the side of its pivot 26 opposite the guideway portion 28,

and the peripheral edge 23^a of this portion of the disk 23 is thus arranged to frictionally engage the wall 24^a, providing coacting frictional retaining surfaces on the bracket and the disk whereby the movable guideway arm 2 is adapted to be held in any position to which it is adjusted without the use of additional or extraneous fastening means, or the necessity of adjusting any fastening means whatever.

In the operation of the device, the repeater, the base portions of which lie in a common plane, is laid upon the top surface of the record which is placed in position for use on the turntable, and the opening 15 and ferrule 16 are engaged with the spindle of the turntable, the spring fingers 17 gripping said spindle. The member 2 is then adjusted so that the recess 30 lies in line with the starting groove of the record, with which the reproducer needle is engaged, and the stop rod 8 is adjusted until its tapered end 9 alines with the final groove of the record. The machine then being set into operation for the playing of the composition, the needle will traverse the record groove and engage the rib 7 at some point in its length and travel along said rib and then along the rod 8 as the composition is being played until the final groove of the record is reached, at which time the needle will pass beyond the end 9 of the stop rod. While the needle is traveling in engagement with the rib 7 and rod 8, the repeater will be held thereby from rotation with the turntable and record, with the result that the machine will operate in the usual way for the playing of the composition. While the repeater is so held from rotation, the spring fingers 17 of its friction clutch ferrule 16 slip around the surface of the turntable spindle. When, however, the needle passes beyond the end 9 of the stop rod 18, the repeater will no longer be held from rotary motion and the spring fingers 17 gripping the spindle will couple the repeater to the spindle for motion therewith and with the record. The reproducer being relatively fixed during this stage of the operation, the needle simply traveling in the final record groove, the rotation of the repeater will result in the edge 21 of the flaring entranceway 20 being brought at some point in registry with the needle which rides over the beveled surface 21 into said flaring entranceway and thence passes through the initial portion of the groove formed by the rods 19 and thence into the delivery portion of the groove formed by the rails 27 and finally into the space or recess 30, whereby the needle is conducted through a spiral path, of a set contour dependent upon the diameter of the record, back to starting position for a repetition of the above-described operation and of the composition represented

by the grooves of the record. It will be evident that by proper adjustment of the parts 2 and 8 the repeater may be set to operate in conjunction with records of any given size and varying in size from minimum to maximum, making the device useful for a repeating action in connection with records of all sizes, including disk records of various styles and various types of machines on which said records are used.

As stated, the device in practice may be made of sheet metal or other suitable material and it may be stamped up to provide stiffening ribs or bosses 31 at proper points 15 to give it any desired strength and rigidity. For the purpose of preventing the device from scratching or otherwise marring the record, such device may be provided on its underside with a layer or contact pieces 32 20 of felt or other suitable material. The device may also be made as plain or ornamental as desired, according to the taste or fancy of the user and the demands of the purchasing public. The structure shown 25 lends itself to a formation which may simulate the general appearance of a coiled serpent, and it may be enameled or otherwise ornamented to delineate more fully the characteristic appearance of a serpent, thus 30 adapting the device to serve as a novelty as well as an article of utility of the character described.

While the construction shown is preferred, it is to be understood that changes in construction, form, proportions and various details may be resorted to, within the scope of the appended claims, without departing from the spirit or sacrificing any of the advantages of the invention.

Having thus fully described my invention, I claim:—

1. In a phonograph record repeater, a frame member comprising oppositely projecting arms connected at their adjacent ends 45 by an offset portion, a stationary needle return guideway section fixed at one end to the outer end of one of said arms and terminating at its inner end adjacent to said offset portion, and a movable needle return guideway section provided with a disk-shaped end portion and a guideway having a flaring entrance carried by said disk-shaped end portion, the said disk-shaped end portion of the movable needle return guideway section being pivotally connected with the offset portion for swinging movement laterally with respect to the stationary needle return guideway section.

2. In a phonograph record repeater, a 60 frame comprising two arcuately curved arms, an offset uniting the inner ends of said arms, a stationary needle return guideway section having a flaring outer end fixed at one side to the outer end of one of said arms 65 and having an inner end of substantially

uniform width terminating adjacent to said offset, a brace lying on the opposite side of said stationary needle return guideway section from the frame arm to which said guideway section is fixed and connecting 70 the opposite side of the outer end of said section to the inner end thereof, and a movable needle return guideway section having an expanded disk-shaped end portion and a needle return guideway with a flaring entrance overlying said expanded disk-shaped end portion, the said expanded disk-shaped end portion being pivotally connected to the offset for adjustment of said movable needle return guideway section laterally with respect to the stationary needle return guideway section.

3. In a phonograph record repeater, a frame member having two oppositely extending arms, an offset uniting said arms at 85 their inner ends, a bracket carried by said offset and overlying the space between the inner ends of the arms, a fixed needle return guideway section having a laterally expanded outer end portion fixed to the outer end 90 of one of said arms provided with a flaring guide channel and having a contracted inner end portion terminating adjacent to said offset and provided with a guide channel of uniform width continuous with the first-named channel, and a movable needle return guideway section provided with a disk-shaped end portion pivoted to said bracket, said movable guideway section having a 95 guide channel provided upon said disk-shaped end portion thereof with a flaring entrance for coaction with the guide channel of uniform width of the fixed needle return guideway section.

4. In a repeating attachment for phonographs, a frame plate including two longitudinally aligned stationary frame members connected by an offset portion and a stationary needle guideway section lying opposite one of said frame members and having its delivery end terminating opposite and in spaced relation to said offset portion, a bracket projecting from the offset portion toward said end of the stationary guideway section, a movable guideway section, and a disk at the receiving end of said movable guideway section partially underlying said bracket and pivotally connected therewith, said movable guideway section having a 110 guideway provided with a flaring entrance end lying at the side of said disk opposite that portion thereof underlying the bracket and movable across the delivery end of the guideway of the stationary guideway section.

5. In a repeating attachment for phonographs, a frame plate including a stationary guideway section, a bracket carried by the frame plate in proximity to but spaced with relation to the delivery end of said stationary guideway section, said bracket having 115 120 125 130

an arcuate friction surface, a movable guideway section, and a disk at the receiving end of said movable guideway section underlying and pivoted to said bracket, said disk having a peripheral friction surface engaging the friction surface of the bracket, said movable guideway section extending tangentially.

from the disk on the side of its pivot opposite that portion thereof underlying the bracket and having a flaring guideway entrance for coaction with the delivery end of the stationary guideway section.

In testimony whereof I affix my signature,

MANUEL HUMBERTO PÉREZ.
